(57) **CLAIM**

The ornamental design for pair of suture tabs, as shown and described.

DESCRIPTION

FIG. 1 is a perspective view of suture tabs showing the claimed design;

FIG. 2 is a top view thereof;

FIG. 3 is a bottom view thereof;

FIG. 4 is an enlarged right side view thereof;

FIG. 5 is an enlarged left side view thereof;

FIG. 6 is a front view thereof;

FIG. 7 is a rear view thereof;

FIG. 8 is a perspective view of suture tabs showing the claimed design;

FIG. 9 is a top view thereof;

FIG. 10 is a bottom view thereof;

FIG. 11 is an enlarged right side view thereof;

FIG. 12 is an enlarged left side view thereof;

FIG. 13 is a front view thereof;

FIG. 14 is a rear view thereof;

FIG. 15 is a perspective view of suture tabs showing the claimed design;

FIG. 16 is a top view thereof;

FIG. 17 is a bottom view thereof;

FIG. 18 is an enlarged right side view thereof;

FIG. 19 is an enlarged left side view thereof;

FIG. 20 is a front view thereof; and,

FIG. 21 is a rear view thereof.

The dashed broken lines in the Figures show portions of the pair of suture tabs that form no part of the claimed design.

1 Claim, 15 Drawing Sheets
